BY

Geo. P. Kimmel. ATTORNEY.

UNITED STATES PATENT OFFICE.

SVERRE QUISLING, OF MADISON, WISCONSIN.

CLOSURE FOR CONTAINERS.

Application filed October 30, 1925. Serial No. 65,810.

To all whom it may concern:

Be it known that I, SVERRE QUISLING, a citizen of the United States, residing at Madison, in the county of Dane and State of Wisconsin, have invented certain new and useful Improvements in Closures for Containers, of which the following is a specification.

This invention relates to a closure means 10 or more particularly a means for connecting together adjacent free edges of two bodies of flexible material.

The primary object of this invention is the provision, in a manner as hereinafter 15 set forth, of a means for connecting free edges of flexible bodies which will be quick and easy to operate, setting up a strong and close connection between the two edges of material.

Another object of the invention is the provision, in a manner as hereinafter set forth, of a structure for connecting together the edges of two bodies of flexible material, comprising a means to set up a trough like structure along one edge of the material having the mouth thereof of less diameter than the interior and a locking cord having a portion of large diameter and a portion of smaller diameter slidably held in a casement formed 25 along the other body of material and designed, when the small portion of the cord is drawn through the casement and the casement arranged in the trough, to be locked thereto by sliding the cord through the casement until the large portion thereof is drawn 30 thereinto to fill the casement and prevent it from being withdrawn through the mouth of the said trough.

The final object of the invention is the provision, in the manner as hereinafter set forth, of a means for securing together two abutting edges of flexible material, quickly and easily, and to set up a strong and unbreakable connection therebetween.

The invention will be best understood from a consideration of the following detailed description taken in connection with the accompanying drawings forming a part of this specification, with the understanding that the invention is not confined to any strict conformity with the showing of the drawings but may be changed and modified

so long as such changes and modifications mark no material departure from the salient features of the invention as expressed in the 55 appended claims.

In the drawings:—

Figure 1 shows partly in side elevation and partly in section, the upper portion 60 of a bag having the closure structure embodying this invention applied thereto.

Figure 2 shows in more detail the mouth of the bag shown in Fig. 1, showing one side thereof turned downwardly or disconnected from the other, as when the mouth 65 of the bag is open.

Figure 3 is a transverse section taken upon the line 3—3 of Figure 1 showing how the two edges of the bag mouth are 70 locked together.

Figure 4 is a transverse section taken upon the line 4—4 of Figure 2, showing the manner in which the two edges of the bag mouth are disengaged.

Figure 5 is a transverse section taken 75 upon the line 5—5 of Figure 2.

Referring now to the drawings in detail wherein like numerals of reference indicate corresponding parts throughout the several views, the numeral 1 indicates a bag of conventional construction, being split along one side at the point 2 to set up flaps 3 and 4 respectively. The opposite side of the bag, from the split side, is sewed to the top, that is the flaps are connected all the way to the 80 top edges thereof.

The flap 3 has the top edge thereof turned over and inwardly upon itself to set up the inner and outer portions 5 and 6 respectively thus forming a sleeve or casement along the top edge of the flap. In this sleeve or casement there is fitted in edge to edge relation, a series of split annular bands 7, the inner and outer portions 5 and 6 of the sleeve lying snugly against the inner and outer faces of the bands as is clearly shown in Figures 3, 4 and 5, whereupon the inner and outer portions 5 and 6 are stitched together transversely of the mouth of the bag as indicated at 8 and are also stitched transversely 95 between the split annular members as is indicated at 9 in Figures 1 and 2. There is thus set up across the top edge of the flap 3 the channel or trough 10 having the mouth

- 11, opening downwardly upon the inner side of the flap 3. As is clearly shown in any one of the Figures 3, 4 or 5, the diameter of the passage 12 through the trough 10 is greater than the mouth 11 of the trough and it is clear that an object positioned within and of sufficient diameter to fill the passage 12, could not be drawn therefrom through the mouth 11.
10. The top edge of the other flap 4 is turned over upon itself to set up the inner and outer portions 13 and 14 which portions are stitched together transversely of the mouth of the bag as indicated at 15, to set up the casement or sleeve 16 across the top edge of this flap 4. The casement or sleeve 16 has one end positioned within and secured in one end of the trough 10 by the stitching 17 thus fixing the edges of the flaps 3 and 4 together.
15. at one side of the bag mouth, the casement 16 being fixed in the trough 10 as above stated. Extending through the casement 16 is an endless cord indicated generally by the numeral 18. Substantially one-half of this cord is of relatively large diameter as indicated by numeral 19 whereas the other half thereof is of relatively small diameter as indicated at 20. The portion 19 which is of largest diameter is of sufficient size to
20. completely fill out the casement 16 when drawn thereinto as is shown in Figures 3 and 5, and the casement 16 when so filled out by the portion 19 of the tie or locking cord is then of sufficient overall diameter to snugly fit in the passage 12 of the sleeve or trough 10.

From the foregoing description the operation of this closure locking structure will be readily understood and is as follows:—

40. Assuming the bag to be open as in Figure 2, the portion 20 of smaller diameter, of the locking cord 18 will be extended through the casement 16 thus allowing the casement to pass freely through the mouth 11 of the trough 10 as shown in Figure 4. The edges of the flaps 3 and 4 are thus easily separated.
45. When it is desired to close the mouth of the bag the locking cord 18, upon the split side of the bag mouth, is drawn upwardly toward the mouth 11 of the trough 10 and due to the fact that one end of the casement 16 is fixed within one end of the trough 10, the other portion of the casement will slip into the passage 12 of the trough together with the portion 20 of the locking cord.

With the casement thus positioned in the passage 12 of the sleeve or trough 10, the locking cord 18 is then drawn through the casement 16 until the portion 19 of larger diameter is drawn into the casement to fill the same and thus causing the casement to fill the passage 12, as shown in Figures 3 and 5. It is clear from this that the casement 16 cannot be withdrawn from the passage 12 of the sleeve through the mouth

11 as it could be if the portion 20 were lying therein and therefore the two edges of the bag mouth are secured together. It is apparent that upon reversing this operation the flaps 3 and 4 may be readily separated.

Although the foregoing description has been confined to a bag structure showing the device applied to the mouth thereof, it is to be understood that the means described for connecting together the edges of flexible material, is not to be confined to use upon bags but may be used upon clothing or in any place where it is desirable to have means for quickly connecting together or disconnecting adjacent edges of material.

From the foregoing description it will be seen that the means herein employed for connecting the material in the manner described is easy to operate, and there is not employed any large number of elements or complicated parts.

Having thus described my invention what I claim is:—

1. A device of the character set forth for connecting the edges of two portions of flexible material, comprising means to set up a rigid trough along one edge of one portion, the interior diameter being greater than the mouth thereof, means to set up a casement along one edge of the other portion having one end fixed in said trough, and a locking cord extending through said casement and having a portion of relatively large diameter and a portion of smaller diameter, said portion of larger diameter when drawn into said casement after positioning the same in said trough, filling and preventing the same from passing the mouth of the trough.

2. A device of the character set forth for connecting the edges of two portions of flexible material, comprising an edge to edge arranged series of split annular elements encased in one edge of one of said portions to set up a downwardly opening trough therealong open at both ends, the interior diameter of said trough being greater than the width of the open side thereof, a sleeve formed along the edge of said other portion and having one end fixed in one end of said trough, and a locking cord slidably positioned in said sleeve and having a portion of relatively small diameter and a portion of relatively large diameter, said portion of largest diameter acting, when drawn into said sleeve after positioning the same in said trough, to fill the sleeve and trough to prevent the removal of the sleeve from the trough.

3. A device for connecting together the edges of two portions of flexible material, comprising a series of annular split bands secured along one edge of one of said portions to set up a trough therealong having

the mouth of less width than the interior diameter thereof and open at each end, a casement formed along the edge of the other of said portions, and a locking cord extending through said casement having a portion of small diameter and a portion of larger diameter, said portion of larger diameter

when drawn through said casement, after positioning the same in said trough, filling the casement and trough to lock the edges 10 of the portions together.

In testimony whereof, I affix my signature hereto.

SVERRE QUISLING.
